(57) **CLAIM**

We claim an ornamental design for a pickle pipe, as shown and described.

DESCRIPTION

FIG. 1 is an environmental perspective view of a pickle pipe showing our new design;

FIG. 2 is a top perspective view thereof;

FIG. 3 is a bottom perspective view thereof;

FIG. 4 is a side view thereof;

FIG. 5 is another side view thereof;

FIG. 6 is a top plan view thereof; and,

FIG. 7 is a bottom plan view thereof.

The broken lines in FIG. 1 depict environmental subject matter only and form no part of the claimed design.
